UNITED STATES PATENT OFFICE.

WILLIAM E. TEKLENBURG, OF CINCINNATI, OHIO.

LUBRICANT-PUMPING MECHANISM.

1,121,777.

Specification of Letters Patent. Patented Dec. 22, 1914.

Application filed October 20, 1913. Serial No. 796,192.

To all whom it may concern:

Be it known that I, WILLIAM E. TEKLENBURG, citizen of the United States, residing at Cincinnati, in the county of Hamilton and State of Ohio, have invented certain new and useful Improvements in Lubricant-Pumping Mechanism, of which the following is a specification.

My invention relates to improvements in lubricant pumping mechanism.

One of its objects is to provide an improved pump, in which the operative parts are all housed and protected from injury and dirt while the adjustments to operative parts and access to valves may be readily made and had from the exterior.

Another object is to provide improved means, whereby the pump may be selectively actuated by hand or power.

Another object is to provide improved pump mechanism, whereby the volume of oil pumped may be positively determined and readily regulated and varied from the exterior.

Another object is to provide an improved assembly of casing, operative parts and valves, whereby the machine work required is reduced to a minimum in quantity and simplicity in nature.

My invention also comprises certain details of form, combination, and arrangement, all of which will be fully set forth in the description of the accompanying drawings, in which:

Figure 1 is a vertical section through my improved mechanism on line *a—a* of Fig. 2. Fig. 2 is a section through the same on line *b—b* of Fig. 6. Fig. 3 is an enlarged sectional detail of the pump cylinder, plunger, and adjusting mechanism detached. Fig. 4 is a sectional detail illustrating the ratchet driving mechanism, on line *d—d* of Fig. 1. Fig. 5 is a rear end view partly in section on line *c—c* of Fig. 6. Fig. 6 is a front end elevation. Fig. 7 is a perspective view of the strainer cap and latch detached.

The accompanying drawings represent the preferred embodiment of my invention, in which A represents a rectangular metal casing, in which the operative parts are mounted and housed. The operative parts and valves are so arranged with reference to the casing, that through holes may be bored in the casing and similarly tapped if required to provide the requisite ports and passages, thereby reducing the work requisite on the casing to a minimum.

B represents the main or operating shaft which is journaled at one end in a blind journal box 2, tapped into the rear end of the casing. The opposite end of shaft B is journaled in a blind recess or bearing in the sleeve 3, which in turn is journaled in a sleeve bearing 4, tapped into the front end of the casing and provided with a packing gland 5. The sleeve 3 outside of the casing has a crank arm 6 keyed thereto and a crank arm 7 loosely journaled thereon. The crank arm 7 is attached by means of an extension rod 8 to some reciprocating part of the mechanism to be lubricated to cause the crank arm 7 to oscillate in unison with the movements of said mechanism. The crank arm 6 has a handle 9, by means of which it may be turned by hand to give an initial charge of oil to the mechanism, or for other purpose, and is also provided with a spring actuated dog 9' or stud to engage a recess 10 in the crank arm 7 to lock said crank arms together and cause them to move in unison. Said stud is disengaged from the crank arm 7 when it is desired to turn crank arm 6 by hand by pulling outwardly on the handle 9.

At the inner end of the sleeve 3, is a crank arm 11 armed with a pawl 12 which engages the teeth of a ratchet wheel 14 keyed upon the shaft B. A pawl 15 pivotally attached to a bracket 16 on the inside of the casing also engages the teeth of said ratchet wheel to prevent it being turned in a reverse direction. Rigidly mounted upon the shaft B is a cam 17, which engages a yoke or strap 18, carried by a rod 19, which is thereby reciprocated endwise. The rod 19 is supported at one end in a recess bored in a boss 20 carried by the casing and at the opposite end in a sleeve 21 threaded into a hole bored in the rear of the casing.

An arm 22 carried by the rod 19 is provided with a measuring pump plunger 24, which reciprocates in a casing or sleeve 25, one end of which is screwed from the inside of the casing into a threaded opening 26 in the lower portion of front of casing A. The cylinder 27 of the measuring pump is adjustably seated in the bore of the sleeve 25, being adjustable endwise therein from the exterior of the casing to predetermine or vary the amount of lubricant forced through the cylinder 27 at each stroke of the plunger. The forward end of the cylinder 27 seats in a recess in a sleeve 28 threaded into the forward end of the threaded opening 26, said sleeve 28 being

provided with a threaded shaft 29 rotatably held in place with reference to the sleeve 28 by a packing gland 30, and with its inner end threaded into the forward end of the cylinder 27 to adjust said cylinder endwise. A pin 31 sliding in a keyway in the sleeve 25 prevents the cylinder 27 from rotating. The lubricant is fed through a strainer 32 into the interior of the casing or reservoir A, from which it enters a port 33 in the sleeve 25 and thence through a port 34 in the side of the cylinder 27, when said port 34 is uncovered by retraction of the plunger 24. The lubricant is expelled from the cylinder 27 by the forward movement of the plunger 24 and escapes through a port 35 in the cylinder 27, and a slot in the inner end of the sleeve 25 to a ball check valve 36 and thence through port 37 to another check valve 38, and thence by tube 39 to a transparent sight chamber 40. The cylinder 27 being normally submerged in oil avoids liability of air or gases entering at the ports 33 and 34 to thereby alter the volume of lubricant pumped through the cylinder 27. The plunger 24 makes strokes of uniform length, and when the plunger is retracted the oil flows in at port 34 as soon as said port is uncovered by the plunger, and continues to flow in until the plunger is fully retracted. On the forward stroke the oil is free to flow in the opposite direction from the cylinder back to the casing A until the plunger again covers the port 34, after which the oil remaining in cylinder 27 is forced through the check valves 36 and 38, hence when there is practically no clearance between the end of the plunger and inner end of the cylinder, the maximum volume of lubricant is being pumped, and correspondingly less volumes are pumped as the cylinder is adjusted endwise in its supports to increase the amount of clearance between the cylinder head and the end of the plunger, due to a portion of the oil in the cylinder not being expelled by the plunger. From the chamber 40 the oil gravitates through a port 41 in the wall of the casing A to a curved recess 42, open on the outer face of said casing at a point *f* where the face of said casing is dressed or faced. A pump cylinder 43 passes through openings 44 and 45 in opposite sides of the casing A, one of which openings 44 is concentric with the curved recess 42, and an enlarged head 46 at one end of the cylinder 43 has a dressed face to make a tight joint with the dressed face *f* of the casing. The opposite end of the cylinder is threaded and provided with a nut 47 and packing ring 48, by means of which said cylinder is firmly locked in place with tight joints at opposite ends thereof. A plunger 49 is seated in the bore of the cylinder 43, and a packing gland 50 prevents leakage from said cylinder.

der. A cross bar 51 connects the plunger 49 with the reciprocating rod 19 outside of the casing, thereby causing said plunger to reciprocate in unison with said rod 19.

Oil is passed from the curved recess 42 through ports 52 to two check valves 53 and 54 and thence into the cylinder 43 through a port 55 as the plunger 49 is retracted. When the plunger 49 moves forward the oil in cylinder 43 is positively expelled through the port 55 and past the check valves 56 and 57 and thence through a pipe line *h* to a point where it is to be used as a lubricant. The valve chambers for the valves 53, 54, and 56, 57, are formed in the enlarged head of the cylinder 43 and are accessible from the exterior of the casing. The valve 36 is also accessible from the exterior of the casing, and also the means for adjusting the cylinder 27.

A detachable sheet metal cap 58 closes an opening at the top of the casing A and permits access to the interior of the casing if required. A stamped sheet metal cap 59 closes the opening to the strainer 32 and is pivotally held in place by a screw 60, and locked in closed position by an integrally formed spring latch member 61 engaging a notch 62 in the top rim of the strainer casing.

In practice one or more of the heretofore described measuring and pumping mechanisms may be mounted side by side in a single casing, or in a casing subdivided by partitions to independently lubricate different portions of a mechanism, measuring and feeding the quantity of lubricant required by each, of a single, or different grades of lubricant.

The mechanism herein illustrated and described is capable of considerable modification, without departing from the principle of my invention.

Having described my invention, what I claim is:

1. A lubricant pumping mechanism comprising a casing, a pump, and pump driving mechanism located within said casing, a rotatable member to transmit motion from the exterior of said casing to said pump driving mechanism, a power driven crank arm loosely journaled on said rotatable member, exteriorly of said casing, a crank arm rigidly mounted on said rotatable member, exteriorly of said casing, and means to selectively engage said rigidly connected crank arm with said loosely mounted crank arm to cause said crank arms to move in unison.

2. A lubricant pumping mechanism comprising a lubricant containing casing, a pump, and pump driving mechanism located within said casing, a rotatable member to transmit motion from the exterior of said casing to said pump driving mechanism, a power driven crank arm loosely journaled

on said rotatable member outside of said casing, a manually operable crank arm rigidly attached to said rotatable member outside of said casing, and latch mechanism to lock said 5 crank arms together to enable said rotatable member to be either manually or power driven.

3. A lubricant pumping mechanism comprising a lubricant pump, a ratchet wheel 10 and mechanism to transmit motion from said ratchet wheel to said pump, a rotatably supported crank arm armed with a pawl to engage and drive said ratchet wheel, a power driven oscillating crank arm loosely journaled on the axle of said pawl carrying crank arm, a manually operable crank arm rigidly mounted upon the axle of said pawl carrying crank arm, and a latch bar operable to engage or disengage said manually operable 15 20 crank arm with said oscillating crank arm to selectively drive said pump manually or by power.

4. A lubricating pump mechanism comprising a casing serving as an oil reservoir, 25 a pump and pump driving mechanism located within said casing, an oscillating member loosely journaled in the wall of said casing and operatively connected inside the casing with said pump driving mechanism, a power driven crank arm loosely journaled 30 on said oscillating member outside of said casing, a manually operable crank arm rigidly connected to said oscillating member outside of said casing, and means to be selectively employed to engage said manually operable member with or disengage it from 35 said power driven crank arm.

5. A lubricant pumping mechanism comprising a cylinder casing, a reciprocating 40 pump plunger located in said casing, a pump cylinder located in said casing and adjustable endwise relative to said casing, said cylinder being provided with an intake port in its side wall to be uncovered by the retraction 45 of said plunger, means to support said cylinder against rotation relative to said casing, and means operable from the exterior of said casing to adjust said cylinder endwise in said casing with reference to said plunger.

50 6. A lubricant pumping mechanism comprising a lubricant containing casing, a pump plunger located within said casing, means within said casing to reciprocate said plunger, a pump cylinder having an inlet 55 port a fixed distance from the inner end of said cylinder to be covered and uncovered by the movements of said plunger, a valve controlled exit port leading from the inner end of said cylinder, and mechanism adjustable 60 from the exterior of said casing to vary the position of said cylinder along its axis relative to said plunger, and to positively lock said cylinder in its adjusted positions.

7. A lubricant pumping mechanism comprising a lubricant containing casing, a reciprocating pump plunger located within said casing, mechanism to reciprocate said plunger, a pump cylinder to receive said plunger, said cylinder being supported in a recess through the wall of said casing and 65 adjustable endwise relative to said plunger from the exterior of said casing, and an exit valve for said cylinder outside of and accessible from the exterior of said casing. 70

8. A lubricant pumping mechanism comprising a lubricant containing casing, a measuring pump having a reciprocating plunger, a pump cylinder adjustable axially to vary the volume of lubricant being pumped, and an exit valve accessible from 80 the exterior of said casing, a force pump having a reciprocating plunger, a cylinder and inlet and exit valves therefor accessible from the exterior of said casing, and means to reciprocate said respective pump plungers. 85

9. A lubricant pumping mechanism comprising a lubricant containing casing, a main driving shaft journaled in journal boxes supported in recesses in opposite walls of said casing and provided with a ratchet 90 wheel and mechanism to reciprocate a pump plunger, a pump plunger driven therefrom, a pump cylinder to receive said plunger, a sleeve constituting one of the bearings for said main driving shaft and journaled in 95 one wall of said casing, said sleeve being provided inside of said casing with an arm carrying a pawl to engage and drive said ratchet wheel, and outside of said casing with a loosely journaled power driven oscillating crank arm and a rigidly connected manually operable crank arm, and means selectively operable to lock said oscillating and manually operable crank arms together. 100

10. A lubricant pumping mechanism comprising a lubricant containing casing, a reciprocating pump plunger located within said casing, means to uniformly reciprocate said plunger, a pump cylinder to receive said plunger located within said casing, and having an intake port in its side wall to be covered and uncovered by the movements of said plunger, a valve controlled exit port from said cylinder, means to prevent rotary movement of said cylinder, and means to adjust 110 said cylinder axially toward and from said plunger, to vary the volume of lubricant pumped. 115

In testimony whereof I have affixed my signature in presence of two witnesses.

WILLIAM E. TEKLENBURG.
